UNITED STATES PATENT OFFICE.

PETER CHRISTIAN, OF JOHNSTOWN, PENNSYLVANIA.

MECHANICAL MOVEMENT.

SPECIFICATION forming part of Letters Patent No. 725,041, dated April 14, 1903.

Application filed July 12, 1902. Serial No. 115,362. (No model.)

To all whom it may concern:

Be it known that I, PETER CHRISTIAN, a citizen of the United States, residing at Johnstown, in the county of Cambria and State of Pennsylvania, have invented a new and useful Mechanical Movement, of which the following is a specification.

This invention relates generally to mechanical movements, and more particularly to a movement especially adapted for use in connection with steam or other engines, the object of the invention being to provide a simple and efficient device by means of which the movement of the driven shaft can be reversed without reversing the movement of the driving-shaft, thereby permitting the engine to continue its movements, but at the same time permitting the driven shaft to be reversed whenever desired.

20 The invention consists also in the novel features of construction, combination, and arrangement, all of which will be fully described hereinafter and pointed out in the claims.

25 In the drawings forming part of this specification, Figure 1 is a perspective view illustrating a mechanical movement embodying my invention. Fig. 2 is a side elevation of the same. Fig. 3 is a plan view. Fig. 4 is a 30 detail illustrating an elevation, the position of the parts just prior to the reversing operation. Fig. 5 is a section on the line 5-5 of Fig. 4. Fig. 6 is a face view of the cross-head, showing the position of the guide-block when 35 the driven shaft is being moved in one direction; and Fig. 7 is a similar view showing the position of the guide-block when the driven shaft is being moved in an opposite direction. Fig. 8 is a detail perspective view of one of 40 the spring-arms. Fig. 9 is a perspective view of the shifting crank or lever, and Fig. 10 is a perspective view of the guide-block.

45 Referring to the drawings, A indicates the drive-shaft, having a crank portion A' and a fly-wheel A², and connecting-rod B is pivotally connected to the crank-arm A', said connecting-rod being also pivotally connected to a reciprocating pitman C, which slides in a suitable guide C', mounted upon a base C², 50 and carries a cross-head D at its forward end, said cross-head working in an open guide-frame E, which is also mounted upon the base

C². The driven shaft F is journaled in a suitable bearing F' and has a crank-arm F² mounted upon the end adjacent to the sliding cross-head D, said crank-arm being provided with a wrist pin F³, which is surrounded by an antifriction-roller F⁴. The face of the cross-head D is recessed, as shown at D', said recess being essentially lozenge-shaped, 60 and in practice I prefer to make the upper and lower angles D² slightly rounded, while the side angles are made acute, as most clearly shown in Figs. 6 and 7, and it will be noted that the sides of the said recess instead of being perfectly straight are slightly curved toward the center of the recess, as most clearly indicated at D³. A guide-block G is pivotally mounted at the center of the recess, the pivot bolt or shaft G' of said 65 block passing through the sliding cross-head D and projecting beyond the opposite face of the same. The guide-block G is made considerably smaller than the recess D'; but its general shape corresponds with the shape 70 of the said recess, its sides being slightly curved, as indicated at G². A shaft-pin G³ is rigidly connected to the inner face of the guide-block G and a short distance to one side of the line connecting two diagonally 75 opposite corners, the said pin G³ passing through a slot D⁴, produced in the sliding cross-head D. As the cross-head D slides back and forth in the guide-frame the wrist-pin of the crank-arm working in the recess 80 between the side walls of said recess and the sides of the guide-block will cause the crank-arm to be revolved, thereby imparting motion to the driven shaft, the wrist-pin tripping over the corner of the guide-block at 85 each angle of the recess of the head D, and the direction of motion will be determined entirely by the way the said wrist-pin trips over the end of the guide-block, and, furthermore, the motion of the wrist-pin will be 90 guided by the shape of the grooved slot into which it is about to move. Thus by referring to Fig. 6 it will be noted that the guide-block is in such a position as to direct the wrist-pin in a direction indicated by the arrow, 95 whereas in Fig. 7 the guide-block is in such a position as to direct the wrist-pin in the direction indicated by the arrow, which is exactly the reverse of the direction indicated in 100

Fig. 6, and it will also be understood that the position of the guide-block is shifted and regulated by the movement of the shifting-pin G^3 , so that by shifting the guide-block 5 from the position shown in Fig. 7 the movement of the driven shaft can be instantly reversed. In order to accomplish the shifting of the pin G^3 and block G, I employ a shoulder-lever or crank-arm H, which is pivotally mounted upon a stub-shaft H' , carried by the head D, said lever or crank having spring-fingers H^2 , rigidly connected thereto, adapted to straddle the shaft G' and operate alternately in opposite directions upon the 10 pin G^3 when the said lever or crank is shifted in alternately opposite directions, and in order to accomplish this movement of the lever H, I employ a lever I, which is bifurcated at its free end, as shown at I', each member having a peculiar curved jaw I^2 , which is adapted to engage the head H^3 of the lever. This lever I is pivotally connected to a hand-lever K by means of a link rod K', and the lever K is provided with the usual thumb-latch K^2 15 and rack-segment K^3 , so that the said lever can be held at any desired adjustment. When the hand-lever K is in one position, one of the curved jaws I^2 will engage the head H^3 of the crank or lever H and shift the lever in one 20 direction or the other. In so shifting the lever the spring-fingers H^2 operate upon the shift-pin G^3 , and consequently shift the position of the guide-block G. When the position of the hand-lever K is reversed, the 25 opposite curved jaw I^2 is brought into position to engage the head H^3 and shift the lever H to the opposite position, consequently reversing the position of the pin G^3 and block G, and, as before stated, this slight reversal 30 of the position of the guide-block is sufficient to produce the reversal in a rotary motion of the driven shaft. In order to lock the lever H in its adjusted position after contact with the bifurcated lever, I employ 35 spring-arms L, which are fastened to the sliding head D above and below the lever H, each head carrying a dog L' , which is adapted to engage the rib or shoulder H^4 , formed upon crank or lever H, said pawls or dogs being 40 adapted to engage the said portions H^4 after the adjustment has been effected, and in order to disengage the said dogs whenever a reversal is to be effected I provide the lugs L^2 , which engage the beveled heads I^3 of the 45 curved jaws I^2 , thereby pressing the spring-arms inwardly toward the sliding head and disengaging the pawls L' from the rib or shoulder H^4 and permitting the crank or lever H to be shifted by its contact with the curved 50

jaws I^2 , it being understood that the beveled head I^3 has disengaged the pawls or dogs L' . 60

It will thus be seen that I provide a simple and efficient mechanical movement capable of use in connection with any of the engines now in common use and by means of which 65 an instant reversal of the driven shaft can be accomplished without reversing the driving-shaft, said reversal being accomplished by shifting the position of the hand-lever, which results in the shifting of the position of the 70 guide-block within the recess of the sliding head.

Having thus fully described my invention, what I claim as new, and desire to secure by Letters Patent, is—

1. The combination with the sliding head having a recess essentially lozenge-shaped, the upper and lower angles being slightly rounded, of the shifting-block pivotally mounted within the said recess, and all substantially the same shape as the said recess, 80 and a shifting-pin carried by the said block and passing through a slot formed in the sliding head, substantially as described.

2. The combination with a sliding head recessed as set forth, of the guide-block pivoted in said recess, the shifting-pin carried by the guide-block, a lever adapted to operate upon the said shifting-pin; together with means for operating the said lever, as specified. 85

3. The combination with the sliding head recessed as set forth, of the guide-block pivoted in said recess and provided with a shifting-pin, a lever adapted to operate upon the said shifting-pin, means for operating the 95 said lever together with means for locking the said lever after the shifting operation has been accomplished, as specified.

4. The combination with the sliding head recessed as set forth, of the guide-block pivoted in the recess and provided with a shifting-pin, a lever having spring-fingers adapted to engage the said shifting-pin, a lever bifurcated at one end and having the said bifurcated members curved to engage the lever for the purpose of shifting the same, and the spring-arms carrying locking-dogs adapted to engage the lever after the shifting operation has been accomplished, said locking-dogs being adapted to engage the bifurcated 100 lever before the reversal of the shifting-lever takes place; together with means for operating the bifurcated lever, substantially as set forth.
